UNITED STATES PATENT OFFICE

EDGAR H. WILSON, OF INGRAM, AND ROBERT W. SCHUETTE, OF MUNHALL, PENNSYLVANIA, ASSIGNORS TO TAYLOR-WILSON MANUFACTURING CO., OF MCKEES ROCKS, PENNSYLVANIA, A CORPORATION OF PENNSYLVANIA

CHARGING DEVICE

Application filed November 21, 1925. Serial No. 70,492.

The present invention relates to charging devices for furnaces or the like and more particularly of the type for charging metal strips into furnaces.

- 5 • Among the objects of the invention is to provide a novel charging device of the type above mentioned and which will be of a single rigid unit, preferably with the frame of the device formed from a single casting and 55
- 10 adapted to enclose and house the driving and operating mechanism in order to maintain the same in neat and clean condition, and to exclude the entry of foreign matter, such as scale, rust, oil and other and similar foreign 60
- 15 matters. The drives may also be entirely enclosed in such frame. This makes for a more compact and self-contained unit. The truck 65
- 20 portions of the unit may also be housed therein and form rigid parts of the structure.
- 25 Another object of the invention is to provide a novel charger adapted to travel before a line or battery of furnaces in which the charger may charge or project metal pieces, such as strips of iron and the like, selectively 70

The invention also comprehends, as a feature thereof, the provision of a novel means for shifting or moving the pieces or strips to be charged into the furnace, from a supporting or charging position to a charging rotor or wheel whereby the latter may seize the same and cast or charge the piece or strip into the furnace. This shifting or moving means preferably is located between the charging 75

30 motor and the door of the furnace and such that it may be moved, when carrying or moving the piece or strip toward the rotor, in a direction toward the furnace or charging direction, while at the same time moving the 80

35 piece or strip toward the roller for charging engagement therewith. In this way the piece or strip to be charged is given an initial movement in the direction of charge so that the seizing of the strip by the rotor will be 85

40 aided by this component movement, thus avoiding the necessity of overcoming the inertia in a strip of skelp if the same were being moved toward the wheel without this initial component movement in the direction of 90

45 charge or if the strip were moving in an oppo- 95

50 site direction. Moving the strips in the direction disclosed by this invention, will also aid in lifting or separating the strips one from the other to disengage any shear hooks 100

or burrs upon the ends of the strips, which might tend to prevent the easy disengagement of a strip from another when operating to move the strip toward the rotor. Such movement will also aid in breaking any adherence that might occur between the strips 105

owing to the same being coated with viscous substances, such as oil. In other words, the strip is given a sliding movement as it is drawn or moved toward the wheel so that an efficient movement of the same may be had and also an efficient seizing of the same by 110

115 the rotor.

The shifting means or mechanism is also so mounted that it can be operated from the rear end of the device where the operator is located, the operation being preferably by manual means extending to the forward end of the machine and readily operated to effect the shifting desired, although the same may be automatically operated under a manual 120

125 control, as desired.

Another feature of the invention is to provide a novel charging rotor of the magnetic type and comprising a disk that is rotatably mounted in position to charge a strip of metal 130

135 when brought into contact with its surface, the surface of the rotor preferably having a series of ribs or the like for the purpose of maintaining the engaging surface or surfaces of the rotor free of foreign matter such as oil, soot, and the like, which might hinder or delay the effective magnetic gripping of the rotor upon a strip to be charged, whatever foreign matter being present on such 140

145 surface or surfaces when engagement occurs, being forced to the edge of the rib and into the spaces between the ribs. In this way an intimate and efficient engagement or magnetic gripping of the rotor with the strips may be effected upon the initial seizure thereof. 145

150 These strips will also aid in maintaining a saturated magnetic condition in the rotor, should the rotor not be saturated. These strips are preferably welded to the periphery 155

160 of the disk and when operating upon the strip 160

effect vibrations, it is believed to destroy adherence thereof with another strip, as the same is being charged. As another feature, the invention comprehends the idea of providing a self-cleaning device such as a scraper adapted to be resiliently engaged with the periphery of a disk in order to maintain the surface clean, at least from foreign matter.

The invention also comprehends the provision of means for supporting the roll in charging position, such means comprising a frame rigid with the support upon which the strips may be located for charging, and locating the frame at one side from the support and preferably in the form of a goose neck extending from the forward end of the support and laterally thereof and then rearwardly, and with a portion, in the form of a head, extending over the support. The rotor 20 is rotatably mounted in the head and the frame or end preferably has a laterally extending arm passing forwardly of the rotor to the opposite side thereof to support one bearing therefor, the other bearing being supported in the head of the frame. In this way a clearance space is provided on the opposite side of the machine whereby the operation of the poke-up bar may be readily effected through the opening or port of the furnace 25 without interference of any projecting part of the machine, the rear end of the poke-up bar being capable of moving in such clearance space. By placing the bracket or arm above the rotor for supporting the bearing 30 on the outside thereof, space is also provided at the sides of the rotor such that the operator in the pulpit at the rear end of the charger may gauge the position of the rotor with reference to the door of the furnace, the 35 lower or charging surface of the roll being substantially on the level with the hearth or fore plate of the door.

Another feature of the invention is to provide the shifting means with magnetic members and preferably mounting the mechanism to rotate about the axis of the rotor and so associated with the same as to provide a suitable and given magnetic gap between the magnetic parts of the shifting means and 40 the magnetic disks of the rotor. This mechanism may be provided with magnetic members of any desired form or shape and adapted to engage with the surface of a strip to be carried to the rotor by the mechanism when shifted. These members are provided with non-magnetic spacers so that any number of members and any number of spacers may be arranged in any given order to adjust the spacing or gaps between the members, so as 45 to vary the magnetic effect thereof in accordance with the weight of the strips to be operated upon.

Scraping mechanism may also be carried by this pick-up means so that it may be moved at the time of shifting, and it also may con-

tain a guard member, preferably in the form of a bar, so located that when any shifting mechanism is moved to bring a strip in contact with the rotor, the bar will be located in position to prevent the striking or slapping of the trailing or rear end of the strip as it is being charged into the furnace by the rotor, and thus preventing the bending of the rear end of the strip. In this way an imperfect charging is prevented.

As another feature of the invention, a novel rotor construction is provided and preferably in the form of a pair of disks which may be capped and having their open ends extending toward each other and provided therein with hubs which have clutching means so that one disk may drive the other, the clutching means also having a centering means in order to maintain the parts co-axial. The hubs may be of non-circular cross-sectional 50 form or square upon which may be placed a spool with an electro-magnetic winding for energizing the disks. The walls of the disks may be provided with a number of grooves or channels for the locating therein of the leads running from the corner or the middle portion of a spool to the tubular shaft of the rotor and to the collectors. The disks are preferably operated by clutch means connected to shafts respectively supported in bearings in the frame and the other end of the arm rigid with the frame and forwardly of the rotor. At the sides of the rotor may be provided hubs affording bearing means for the shifting mechanism with members 55 thereof rotatably mounted upon these hubs and carrying annular bosses or rings of magnetic material and gauged to provide a space between the same and the outer faces of the disks to form magnetic gaps. By making 60 the inner hubs square or non-circular it will be impossible to turn the spool relative to the rotor by reason of any inertia.

The invention also comprehends the construction of a frame with a head portion in 65 which is supported a motor and the driving means from the motor to the rotor, the same being entirely encased or housed in the head of the frame.

Another feature of the invention is to provide the charger with guiding means below and above as well as at both sides of the strips so that when the same is being charged by the charging rotor into the furnace, the strips will be maintained in charging line. The upper guard will prevent the rising of the strip or skele from the charging path or if the same tends to rise, it will be engaged by the guard which will direct it back into the proper path. The lower guard similarly will prevent the dropping of the strip and guide it back into the path of charging. Upon the support are preferably provided side guiding means, each of which may be laterally adjusted in accordance with the width of the 130

strips to be used, and of which one is preferably movable and operable by manual means from the pulpit so that it may be withdrawn out of position when a new load of strips or skelp is being transferred or loaded upon the support. The guiding members at the forward end of the machine for guiding against rising or falling of the strips may also be adjustable if desired.

Another guard, preferably auxiliary to the lower guard may also be comprehended by the invention, this guard preferably being located to prevent the trailing end of a flying strip from having such contact or engagement with the lower guard as would produce a retarding effect in the strip or otherwise prevent a full and correct charging of the strip in the furnace.

Another object of the invention is to provide novel means for transferring and loading the strips upon the support for charging. This means preferably is operated by suitable sources of power upon the machine and specifically comprises endless chains adapted to receive a load of strips and carry the same laterally to supporting position upon the support, the chains forming elements of the support. The strips may be stopped in position for charging by suitable stops at the sides of the support, the stops being preferably adjustable depending upon the width of the strips being operated upon. The transfer chains may be located at spaced intervals and between the same may be a second number of supporting means or elements in the form of a series of rollers acting as auxiliary skids. These may be slightly lower than the surface of the chains but are located to maintain the strips in substantially level condition, but as to prevent the deflecting of the parts of the strips between the chains and also to aid in properly supporting the strips if they be warped. The transfer means may also be provided with means for effecting the loading of a stored amount of strips to the chains for the latter to transfer the same. Such means, specifically, may be provided with dogs pivotally supported upon the support so that when the latter is moved along the tracks in front of the furnaces, the dogs may pass under a load or pile of skelp or strips resting upon stationary skids or rails until the dogs pass beyond the same, and then the dogs may spring upwardly and a reverse movement of the machine and support will bring the dogs into engagement with the pile and move the same from the stationary skids and upon the chain skids. The travel of the latter will then move the pile into charging position upon the table or support and against the stops.

Other features, objects, advantages and capabilities are comprehended by the invention as will later appear and are inherently possessed thereby.

Referring to the drawings showing an embodiment of the invention:

Fig. 1 is a top plan view of a charging machine constructed in accordance with the invention.

Fig. 2 is a side view in elevation of the same.

Figs. 3 and 4 are fragmentary top plan views of the machine more in detail.

Fig. 5 is a view in side elevation of the head portion of the charger and a fragmentary sectional portion of a furnace.

Fig. 6 is a transverse sectional view taken through the machine in a plane represented substantially by line 6-6 in Fig. 4 of the drawings.

Fig. 7 is a transverse sectional view of the same taken in a plane represented substantially by a line 7-7 in Fig. 4 of the drawings.

Fig. 8 is a transverse sectional view taken through the head of the machine and in a plane represented by line 8-8 in Fig. 5 of the drawings.

Fig. 9 is a transverse sectional view taken through the charging rotor mechanism in a plane represented by line 9-9 in Fig. 8 of the drawings.

Fig. 10 is a view in elevation of a part of the same as taken in a plane represented by line 10-10 in Fig. 9 of the drawings.

Fig. 11 is a fragmentary sectional view through the charging rotor and taken in a plane represented by line 11-11 in Fig. 8 of the drawings.

Fig. 12 is a fragmentary sectional view taken in a plane represented by line 12-12 in Fig. 13 of the drawings.

Fig. 13 is a fragmentary view in end elevation of the charger roll or rotor mechanism and showing the use of a cleaning scraper.

Fig. 14 is a longitudinal fragmentary sectional view taken in a plane represented by line 15-15 in Fig. 4 of the drawings.

Fig. 15 is a transverse fragmentary sectional view taken in a plane represented by line 15-15 in Fig. 4 of the drawings.

And, Fig. 16 is a fragmentary plan view of an end of the chain skid feature.

Referring now more in detail to the drawings, the embodiment selected to illustrate the invention is shown as comprising an integral frame or housing 1 preferably formed from a single casting so as to form a single unit having truck portions 2 and 3, a supporting frame portion or goose neck 4 having a head 5 for carrying a charging roller 6, the upper part of the frame 1 having a means, hereinafter more fully described, for supporting strips of material to be charged. The truck portions are supported by suitable wheels 7 and 8 of which wheels 8 are secured to the ends of a shaft 9 extending the length of the machine at one side thereof, the shaft at the middle thereof being connected through suitable driving mechanism connected to a driving motor 10 carried within the

130

housing or frame 1. By driving the shaft 9 from a middle point thereof, an even or equal driving of the wheels 8 will be effected and thus overcome the disadvantage of driving unequally by reason of unequal torsional strains in shafts of unequal lengths. The wheels 7 and 8 are adapted to travel over the rails 11 and 12 arranged parallel to a battery of furnaces 13. At the rear end of the frame or housing 1 is suitably supported a 10 pulpit 14 in which the operator is located when operating the mechanism, the pulpit having a platform 15 and a seat 16 for the operator.

15 At the forward end of the machine is provided a frame portion or member secured rigidly with the end of the machine in any suitable manner and extending forwardly and laterally and also upwardly to form a 20 goose neck 4 and then extending rearwardly to a head 5. The latter carries laterally a motor 17 mounted upon a suitable bracket 18 rigid with the head 5 and adapted to drive through a set of gears 19 operating in oil in 25 a gear housing 20. This train of gears drives a shaft 21 connected to the charging rotor 6 for rotating the same. Extending laterally from the head 5 and forwardly of the rotor is a bracket or arm 23 having an extending 30 portion 24 carrying a bearing 25 for a shaft 26, the latter being connected rigidly with the opposite side of the rotor 6. The shaft 21 has a bearing 27 carried by the gear housing 20 and the head 5 as shown in Figs. 3 35 and 8 of the drawings.

Referring more particularly to Fig. 8, showing the charging rotor mechanism in detail, the shaft 21 is secured to a gear 30 of the gear mechanism 19 by suitable means, such as a key 31, and suitably supported in 40 the bearing 27 having a bushing 32. The outer end of this shaft 21 has a flange 33 bolted to a hub portion 34 of a magnetic disk 35, by means of bolts 36. The flange 33 has 45 coupling grooves 37 adapted to receive thereinto tongues 38 formed integral with the end of the hub 34. The end 57 of the shaft 21 is concentric to the axis of the shaft and fits into a concentric recess 59 formed in the hub 34 for holding the parts centered or co-axial. On the opposite side the shaft 26 is tubular 50 and rotates in a bushing 29 in the bearing 25, and at its inner end has a flange 39 bolted by bolts 40 to a hub portion 41 formed upon the outer part of the disk 42 of the magnetic 55 roll or rotor. The flange 39 has clutch grooves 43 for the reception thereinto of ribs 44 formed integral with the hub 41. The end 58 of the shaft is concentric to the axis of the 60 shaft and rotor, and fits into a recess 60 formed in the hub 41, to hold the parts co-axially.

The disks 35 and 42 are of magnetic material and of circular form and are cupped to 65 provide peripheral portions 45 and 46 with

the open ends of the cupped disks directed toward each other and provided with a space therebetween in which is located a non-magnetic ring 47 filling the magnetic gap between the disks. Upon the periphery 45 and 70 46 of the disks 35 and 42 may be provided a plurality or series of ribs 48 and 49 located upon one disk alternately with reference to those on the other disk, or in other words, in staggered relation. These ribs are located 75 with spaces between them so that when the peripheries of the disks of the charging roll engages with the surface of a strip of metal, a self-cleaning action will be effected upon the engaged surfaces of the ribs of any foreign matter that might be adhering thereto or brought into engagement therewith from the strips or otherwise. This cleaning action appears to be effected by a forcing back of the 80 thin film or the like, to the rear edge of the 85 rib and into the space provided between the adjacent ribs, the foreign matter thus forced into this space accumulating therein or being cast therefrom by centrifugal force. In this way, if any oil, soot or other like and similar 90 foreign matter adheres or tends to adhere to the engaging surfaces of the rib, it will be immediately removed and the surfaces maintained clean and neat so that a correct and 95 efficient engagement or magnetic seizure of the strip by the rotor may be immediately effected. It is also believed that a vibration is effected in the strip so engaged so as to 100 shape the strip loose from adhering tendencies of the other strips.

Within the disks are provided central hubs 50 and 51 preferably formed integral with the disks 35 and 42 respectively, and provided at the inner ends of the hubs with inter-engaging clutch tongues and grooves 52 and 53 whereby the disk 35 may drive through the hub 50 to the hub 51 and thence to the disk 42, and also to the shaft 26 which is clutched with the disk 42 by way of the hub 41. In other words the shaft 21 is clutched with the hub 34 of the disk 35, and the latter by way of the hub 50 is clutched to the disk 42 by way of the hub 51, and the disk 42 is clutched by way of the hub 41 to the shaft 26. This provides for a positive driving of 110 all the parts.

The disks 35 and 42 are centrally apertured to receive a bolt 55 for holding the disks and hubs together as shown. Centrally within the ends of the hub is located a centering disk or ring 56, the function of which is to properly center the hubs 50 and 51 co-axially. Similarly the ends of the shafts 21 and 26 are provided with centering bosses 57 and 58 extending into circular recesses 59 and 60 formed in the outer ends of the hubs 34 and 41. In this way the driving parts are maintained in co-axial relation.

The hubs 50 and 51 are preferably non-circular or square in cross-section and carry 100

5 a spool having a winding or coil 63 having leads 64 and 65 passing through groove 66 and passages 67 and 68 to a central passage 69 provided in the tubular shaft 26, the leads terminating in connections to slip rings 70 and 71 against which engage or contact brushes 70^a and 71^a connected to leads 72 and 73 from a power circuit, the brushes 70^a and 71^a being suitably insulated as is usual in such cases.

10 As shown in Fig. 9, the disk 42 is also provided with other lead passages 74, 75 and 76 in the form of channels or grooves formed in the side wall of the disk. It will be noted 15 that the channels 66 and 75 are located so as to receive or lead off the wire or lead that might proceed from a corner 77 of the spool, while the channels or grooves 74 and 76 are located so as to receive the wires or grooves 20 which might proceed from the spool from the side thereof, depending upon the method of winding and running off the leads.

25 For the purpose of enabling the moving of strips successively from a pile to the charging wheel, a shifter means is provided and which comprises a pair of rings 80 and 81 rotatably supported upon bushings 82 and 83 fastened to the hubs 34 and 41 of the disks 35 and 42. These rings have rearwardly extending portions or arms 84 and 85 carrying a cross shaft 86 to which is pivotally connected the hub 87 of a link 88 pivotally connected at its upper end to a lever 89 fulcrumed upon a bracket 90 secured to the arm portion 30 of the arm for supporting the outer bearing of the rotor. Depending from the shaft 86 is a pair of arms or links 91 and 92 carrying a shaft 93 upon which are supported a number of magnetic contact members or 35 blocks 94 and 95 and a number of non-magnetic spacers 96. In this structure the parts 84, 85, 91, 92, 94 and 95 are magnetic, and the parts 86, 87, 88, 93 and 96 are non-magnetic. The spacers 96 may be of any suitable thickness and of any number and may be located 40 on either side of the members 94 and 95 so as to provide varied non-magnetic gaps between the members or blocks 94 and 95 themselves, and also between them and the arms 91 and 92. In this way the magnetic flux may be varied in accordance with the weight 45 of the strips to be acted upon. The side members 84 and 85 are also preferably provided with shoulders 84^a and 85^a to act as limit stops for arms or links 91 and 92 should the magnetic flux of the rotor tend to draw the links and the parts connected thereto, toward the 50 rotor, thus preventing the shifting mechanism from engaging the rotor and becoming damaged or damaging the rotor.

55 The lever 89 is secured to a shaft 100 to which is also secured an arm 101 carrying a weight 102 acting as a counterweight, the latter being adjustable along the arm 101 as desired. To the shaft 100 is also secured an

arm 103 to which is pivotally connected a turn-buckle link 104 which is in turn connected at its lower end pivotally to a crank 105 rotatably supported in the goose neck 4. The other end of the crank 105 is connected to a rod 106 extending rearwardly through the housing 1 of the machine and being connected at its rear end to a lever 107 suitably fulcrumed in the frame 1 and in turn pivotally connected to a turn buckle link 108 adjusted to be operated by a hand lever 109 fulcrumed upon a bracket 110 in the pulpit. It will be apparent from the above that when the operator pushes the lever 109 forward it will effect the lowering of the magnetic members or blocks 94 and 95 into contact with the top strip 111 of a pile 112, and a reverse movement of the lever 109 will cause the raising of the magnetic rollers 94 and 95 and the forward end of the strip 111 into position to be engaged by the charging roller 6. As the members or blocks 94 and 95 are raised with the strip 111 it will be given a forward movement toward the furnace so that by the time when the charging rotor 90 seizes the strip, the initial movement of the strip 111 will be in aid of the direction of charge by the charging rotor, thus avoiding the overcoming of the inertia of the strip if the same were to be raised or moved in an opposite direction before contacting with the charging wheel. The counterweight 102 will hold the shifter means in upper position until operated by the operator.

95 The rings 80 and 81 are also provided with annular bosses 113 and 114 designed to lie at a given distance from the outer faces of the disks 35 and 42 so as to form an annular magnetic gap between each ring and each disk. It will thus be apparent that the magnetic flux set up in the disk by the energizing of the coil 63 will pass through the gaps into the ring, and the arms 84 and 85 and the parts connected to the rollers 94 and 95 for engaging the metal strips.

100 The rings 80 and 81 are also provided with forwardly extending portions 115 and 116 carrying a shaft 117 which acts as a guard against which the rear or trailing ends of the strip may hit to be guided to the charging path and also to prevent the retarding of the flight of the strip being charged. When 105 charging strips of different weights and different thicknesses, the strips may sag or drop more or less beyond the line of contact 115 thereof with the periphery of the charging rotor, and as the strip is being longitudinally projected by the rotor a reflex action in the sagging or drooping portions may be effected such that as the trailing end of the 120 strip approaches the rotor, it may not be passed by the rotor in proper flight but might be thrown downward or retarded and a full flight charging be prevented. By placing a 125 guard bar 117 a suitable distance ahead of the 130

rotor, the deflected portion of the strip may be engaged by this bar and caused to be properly guided to the rotor and hence avoid the possible disadvantages above mentioned.

In the event of using a charging roller or rotor having a smooth surface 118, the shaft member 117 may support thereon a scraper 119 having a bevel 120 pressing against the periphery 118 of the charging rotor. The scraper may be supported at its lower edge into slotted members 121 and 122 and secured in place by suitable securing elements or screws 123. A spring 124 reacting between one of the members 122 and the arm 115 will constantly resiliently press the scraper 119 against the periphery 118 of the rotor. Any oil or other foreign material adhering to the surface of the rotor will be continually cleaned therefrom by the scraper. With sufficient pressure between the bevel of the scraper and the surface of the rotor, any thin film of oil or the like adhering to the rotor surface may be crowded or forced back sufficient to be scraped off with the remainder being removed at the edge of the bevel. The shaft 117 will still function as a guard means for the rear end of the strip.

When charging the strips, it may occur that the strips are not thrown in exact line but may rise or fall from their charging path or even swing laterally so that the strip may not properly enter into the furnace. In order to correct any such tendencies, suitable guard means is provided comprising an upper guard member or plate 125 secured to the side of the neck 4 by suitable brackets 126 and 127, and a lower guard member or plate 128 carried by the bracket 129 and the bracket 129^a secured to the end of the frame 1, as clearly shown in Fig. 6 of the drawings. Also at one side of the frame 1 may be located a number of stops 130 extending vertically upward at one side of the pile 112 of the strips. These stops are adapted to be moved or adjusted laterally of the machine by means of slot and bolt connecting means 131 of any suitable type, these stops being adjusted into proper position depending upon the particular width of the strips being charged. On the opposite side of the pile 112 of the strips, may be placed another side guiding member 132 extending upwardly and being adjustably carried by means of a pin and slot arrangement upon a shaft 133 rotatably mounted in a bracket 134 and a suitable bearing carried by the frame 1, the other end of the shaft being connected to a crank 135 connected by a pull rod 136 having at its rear end a handle 137 and a notched portion 138 adapted to selectively engage with a latch 139. By operating the handle 137 the operator may cause the lateral guide 132 to extend upwardly or to move downwardly to clear the space at the side of the pile for the charging or transferring of a new pile of strips upon the table or support of the ma-

chine. After the pile has been placed in position upon the machine, the guard member 132 may again be moved into upwardly extending position. It is adjustable along the shaft 133 for use with different widths of strip material to be charged. The notches in the section 138 are for selectively holding the projection 132 in either upright position or in position to be clear of the space above the table of the machine. It will thus be apparent from the above that should the strip 111 be caused to rise or fall or even to swing laterally from the normal charging path, the guides 125, 128, 130 and 132 will act to bring the strip back to its normal path and cause it to travel in the proper line into the furnace.

As the strip is completing its flight from the machine, it might occur that the trailing end dips or sags, whether from deflection in the strip or from changing position. Should this dipping or sagging be great, the trailing end may so engage or strike the lower guard 128 as to effect a retarding of the flight and thus prevent a correct arrival of the strip in the furnace. To avoid this, an auxiliary guard member, in the form of a bar 128^a may be located ahead of the guard 128 and at a point such that as any trailing end of a strip tends to sag or incline beyond a normal path, the rod 128^a will act to aright it by being engaged by the strip end portion before its arrival at the guard 128.

As before stated, the machine may be caused to travel along the rails 11 and 12 before a battery of furnaces, by means of the motor 10 which acts as the driving means for the traveling of the machine laterally. The control of the drive is by any suitable means located in the pulpit of the operator. The strips are usually located in piles upon stationary skids or rails at the end of the course of the machine. For the purpose of conveying these piles to the table of the machine, suitable skid means is provided in the form of endless chains 140 operating over sprockets 141 and 142 of which the latter are secured to a driving shaft 143 suitably driven by driving gearing from an operating motor 144 enclosed in the housing 1. The sprockets 141 are rotatably supported by suitable shafts 145 carried by adjustable members 148 supported in lateral extensions 146 at one side of the machine, the members 145^a being adjusted by way of screws 149 to give the chains the desired tension. The lower section of the chains may pass into channeled guide 147 shaped to give clearance for the gearing of the driving motors in the housing.

When it is desired to convey a pile of strips from the stationary skids, the machine may be caused to travel over the rails 11 and 12 until the projecting portions 146 pass beneath the pile of strips and in between the stationary skids, when the machine is brought to a stop. The chains in this position of the ma-

chine will now lie beneath the pile. The projecting portions 146 are also provided with dogs 150 pivotally supported in suitable recesses and on the pivots 151 and have noses 152 adapted to engage with a stop lug 153 secured to the member 146. Springs 154 normally tend to hold the dogs 150 in upright position, but permits the dogs to return downwardly toward the left when viewed in Fig. 7 of the drawings. When the machine has been moved to bring the projection 146 under the pile of the strips, the dog 150 will hit the same and be pressed downwardly into the recess in the part 146, until the dog passes to the other side of the pile, when the spring 151 will raise the dog. If the machine is now caused to be traveled in the opposite direction, the dog 150 will engage the pile and cause the same to slide to the end of the stationary skids and to drop upon the chains 140. The stationary skids are usually placed with their surfaces about one-half of an inch above the top surfaces of the chain, so that the drop of the pile upon the chain is without danger of spilling.

The driving motor for the chains 140 may now be put into operation and the pile of strips will be caused to travel to the charging position thereof at the top of the machine, until the pile strikes against the stops 130, these having been adjusted in proper position depending upon the width of the strips to be used. The continued movement of the chain will not have any effect further upon the strips but will slide under the pile until the operator has had an opportunity to stop the motor. The operator may then operate the handle 137 for raising the side guiding projection 132 into upright position on the opposite side of the pile from the guide members 130.

If the strips be thin and apt to deflect between the chains 140 or if they be slightly warped, auxiliary skids are provided in the form of a series of rollers 160 arranged serially in a channel between the angle bars 161 and 162 upon cross members 163 secured to the top of the frame 1. The top surfaces of these rows are preferably about one-quarter to one-half inch below the top surfaces of the chains, so that if there be a deflecting of a portion of the strips between the chains, the deflected portions will come to rest upon these auxiliary skids or rolls 160. If the strips are bent or warped, and if the rolls 160 were at the same level as the chains, the rolls 160 might support the strips rather than the chains, and therefore the travel of the chains for transferring the strips toward the stops and into charging position, might not be effected, and for this reason the top surfaces of the rolls 160 are made slightly lower than the top surfaces of the chains.

Each furnace has an opening 170 and a hearth or fore plate 171 at the lower part or

threshold of the opening, the plate 171 being supported by a bracket 172 riveted to an upright 173 at the front of the furnace.

Referring to Figure 6 of the drawings, it will be noted that the opening of the furnace is in the form of a segment of a circle and that the lower surface of the charging rotor or wheel 6 is substantially on the level with the threshold of the charging opening of the furnace. By having spaces on each side of the charging wheel, the operator has a direct line of vision from the pulpit to the ends of the opening 170 on each side of the charging rotor and may thus directly and exactly gauge the position of the machine in this manner, as clearly shown in Fig. 6 of the drawings. Also by having the support for the motor for driving the rotor and the rotor to one side of the charging space, and leaving the opposite side open and free, the man operating the poke-up bar is able to do so freely by the swinging of the rear end of the bar into the space between the rotor 6 and the top of the table or support of the machine.

In operation the machine may be caused to travel to the end of the rails 11 and 12 where it may pick up a load or pile of strips from the stationary skids. The movement of the machine with the dogs 150 will cause the piles to move upon the chains 140. Operation of the chain motor will then cause the pile to travel toward the stops 130, at which time the chain motor may be stopped. In the meanwhile, the operator has operated the handle 137 so as to raise the side guiding projection 132 in upwardly extending position. In the meanwhile the machine may be caused also to move along the rails 11 and 12 to the desired furnace to be charged, and the operator may gauge the position of the machine by the relative position of the charging roller with the end portions of the door 170 as clearly shown in Fig. 6 of the drawings. It will be understood that the motor 17 on the head of the machine is operating the magnetic charging rotor at high speed, and also suitable current is operating in the coil of the rotor to energize the same and the magnetic parts affected thereby.

With the pile of strips in charging position, the operator will operate the lever 109 and cause the magnetic members 94 and 95 to descend and engage with the top strip 111 of the pile. The opposite movement of the lever 109 will cause the strip to move forward and upwardly toward the charging wheel. As soon as the strip engages with the latter, the wheel will seize the same magnetically and cast or project the strip longitudinally through the opening 170 into the furnace and at the right distance therein.

While we have herein described and upon the drawings shown but one embodiment of our invention, it is to be understood that the

same is not limited to the particular embodiment disclosed, but that other features, constructions, arrangements of parts and details are comprehended by the invention without departing from the spirit thereof.

Having thus described the invention, we claim:

1. In a charging device having a magnetic charging rotor, means for moving a metal piece toward the rotor and the place to which the piece is to be charged and comprising a magnetic member engageable with the piece, and means for moving said member toward the rotor while at the same time moving toward said place. 10
2. A device for charging metal bars into a furnace comprising a support for the bars, a magnetic charging rotor, a shifter located between the rotor and the furnace and movable to and from the furnace and also to and from the bars on the support and adapted to shift a bar toward the furnace and toward said rotor for engagement therewith. 20
3. A device for charging metal bars into a furnace comprising a movable support for the bars, a frame mounted in fixed relation to said support, a magnetic rotor carried by the frame, shifting mechanism carried by the frame between the rotor and the furnace, and means for moving said mechanism into contact with a bar for moving said bar toward said furnace and toward said rotor for engagement therewith. 30
4. A charging rotor, comprising cupped disks arranged with their open ends toward each other, non-circular hubs therein, an electro-magnetic winding on said hubs, said hubs having clutch elements whereby one hub may be driven by the other. 35
5. A charging rotor comprising cupped disks arranged with their open ends toward each other, a square electro-magnetic coil in said disks, and channels in the disks for selective passage of the leads from the coil from either a corner or a side thereof. 40
6. In a charging machine for metal pieces, a charging rotor comprising hubs, means for rotatably mounting the rotor and hubs, and shifter means rotatably mounted on said hubs and adapted to shift a piece of metal to said rotor for charging operation. 50
7. In a charging machine for metal pieces, a charging rotor comprising hubs, means for rotatably mounting the rotor and hubs, shifter means rotatably mounted on said hubs and adapted to shift a piece of metal to said rotor for charging operation, and a magnetic gap means between said rotor and said shifter means. 55
8. A device for charging metal strips into a furnace, a charging rotor therefor, means for moving a strip of metal to the rotor, and guard means located adjacent the rotor for preventing the trailing ends of the strips striking the rotor. 60

9. A device for charging metal strips into a furnace, a charging rotor therefor, means for moving a strip of metal to the rotor, a guard connected to and movable with said strip, moving means to be brought into place to guard against the striking of the trailing ends of the strips when being charged by the rotor. 70

10. A charging device for metal strips, comprising a support having means whereby the support may travel sidewise, transfer means on the support, dogs on the support adapted when the support is moved in one direction to pass under a load of strips carried by storing skids and to engage and move said load of strips to remove the same from the skids and to load the strips upon the transfer means, and means for operating the transfer means for moving the strips to charging position on said support. 75

11. In a charging machine for metal pieces, a charging rotor having a hub of magnetic material, a non-magnetic bushing on said hub, a magnetic shifter means on said bushing and being adapted to move a piece of metal to the rotor for charging operation. 80

12. In a charging machine for metal pieces, a charging rotor having a hub of magnetic material, a non-magnetic bushing on said hub, a magnetic shifter means on said bushing and being adapted to move a piece of metal to the rotor for charging operation, said shifter means and said rotor having means for providing a magnetic gap between said rotor and said means. 85

13. In a charging machine for metal pieces, a charging rotor having a hub, means for rotatably supporting the rotor, means for driving the rotor, a bushing on said hub, and a shifter on said bushing for moving pieces to the rotor for charging. 90

14. A device for charging metal strips into a furnace, comprising a support for the strips, a rotor for charging the strips into the furnace, means for moving a strip to the rotor for charging thereby, means for guiding the strip being charged, said guiding means comprising a guide member located below the charging path to guard against the strips being charged too low, and a transverse rod in the charging path ahead of the last mentioned guiding means and located to be engaged by the depressed rear end of a flying strip irregularly charged. 110

In witness whereof, we hereunto subscribe our names to this specification. 115
